UNITED STATES PATENT OFFICE.

DANIEL W. SHOYER, OF NEW YORK, N. Y.

DESIGN FOR A HAMMOCK.

40,370.

Specification for Design.

Patented Nov. 23, 1909.

Application filed September 30, 1909. Serial No. 520,427. Term of patent 7 years.

To all whom it may concern:

Be it known that I, DANIEL W. SHOYER, a citizen of the United States, residing in the city of New York, borough of Manhattan, in the county and State of New York, have invented a new, original, and ornamental Design for a Hammock, of which the following is a specification, reference being had to the accompanying drawing, forming part thereof.

The figure is a plan view of a hammock showing my design.

I claim:

The ornamental design for a hammock as shown.

DANIEL W. SHOYER.
